UNITED STATES PATENT OFFICE.

LOYAL M. DODDRIDGE, OF STANTON, MICHIGAN.

ENVELOP.

1,142,942.

Specification of Letters Patent. Patented June 15, 1915.

Application filed March 29, 1915. Serial No. 17,901.

To all whom it may concern:

Be it known that I, LOYAL M. DODDRIDGE, a citizen of the United States, residing at Stanton, in the county of Montcalm and 5 State of Michigan, have invented certain new and useful Improvements in Envelops, of which the following is a specification, reference being had to the accompanying drawings.

10 The present invention relates to new and useful improvements in envelopes and as its principal object aims to provide a device of this character which is extremely simple in construction and may, therefore, be cheaply 15 manufactured.

A further object is to provide an envelop in which the film of adhesive material is applied to an inner flap carried by the back of the envelop so that it will be possible to 20 wet the closure flap when the envelop is to be sealed, without requiring that the adhesive material itself be passed over the moistening element.

The above, and other incidental objects 25 of a similar nature, which will be herein-after more specifically treated are accomplished by such means as are illustrated in the accompanying drawings, described in the following specification, and then more 30 particularly pointed out in the claims which are appended hereto and form part of this application.

With reference to the drawings, wherein 35 there has been illustrated the preferred embodiment of this invention, as it is reduced to practice, and throughout the several views of which similar reference numerals designate corresponding parts, Figure 1 is a plan view of the back of the envelop in solid 40 lines, the blank from which the envelop is formed, being indicated in dotted lines; and Fig. 2 is a plan view of the flap sealing strip and the connecting strips of the back wall section, showing them in the relation which 45 they assume when applied to the back wall of the envelop.

The envelop of the present invention is formed from a single blank designated as 50 an entirely by the letter A. This blank includes a back piece 10, a front piece 11, a closure flap 12 and the terminal extensions 13 which, when the blank is properly folded, constitute a portion of the back. The back 10 is irregular in shape, its outer edge being 55 curved, as indicated at 14 and its end edges, indicated at 15, being outwardly convergent

and diagonal with respect to the member 11. The outer edges 16 of the extensions 13 are diagonal and extend parallel to the edges 15. The end edges 17 of the extensions 13 60 are curved on a radius corresponding to the radius of the curved edge 14 of the back, so that they will form continuations of this edge when the blank is folded in the manner shown in Fig. 1. Upon reference to this 65 figure, it will be seen that the back piece 10 and front piece 11 are folded on the crease line B—B to dispose the back piece against the front piece. The terminal extensions 13 are then folded on the crease line C—C and 70 are thus disposed so that their outer edges 16 mate with the edges 15 of the member 10 on a line which extends diagonally with respect to the lower edge of the envelop. After the blank has been thus shaped, a pair 75 of sealing strips, indicated at 18 are applied to the inner face of the back piece to connect this member with the extension 13. The sealing strip 19 is then applied to the inner face of the back piece, at the curved 80 edge thereof. This sealing strip 19 is longitudinally curved, to conform to the curved edge 14 and is disposed with its outer edge portion lying on the edge 14 so that the flap 12 may be folded, and after being properly 85 moistened, engaged with the sealing strip to close the envelop.

I desire to direct particular attention to the fact that in the present envelop, the strip 19 which carries the adhesive material for 90 sealing the envelop, need not be moistened and that the flap 12 which is not provided with any adhesive material, is the element which may be moistened. The particular advantage in this construction is that when 95 the flaps are moistened for sealing, there is no mucilage to come off the flap and deposit on the sponge or other moistening element employed.

While I have shown the members 18 and 100 19 as being separately formed and have so described them, I desire it understood that they may be cut from a single blank of material.

In reduction to practice, it has been found that the form of this invention illustrated in the drawings, and referred to in the above description as the preferred embodiment is the most efficient and practical; yet realizing that the conditions concurrent with the 105 adoption of this device will necessarily vary, it is desirable to emphasize the fact that 110

various minor changes in the details of construction, proportion and arrangement of parts may be resorted to, when required, without sacrificing any of the advantages of 5 this invention, as defined by the appended claims.

What is claimed is:—

1. An envelop including a rectangular front piece, an irregular back piece of less 10 length than the front piece, terminal extensions formed on the front piece, said extensions being disposed to mate with the back piece to form in connection therewith the back wall of the envelop, a sealing strip 15 connecting the back piece and extensions, a flap formed on the front piece, and a sealing strip carried by the back piece and on the inner face thereof for sealing the flap, said sealing strip being longitudinally 20 curved and having its outer edge portion lying beyond the adjacent edge of the back

piece, whereby the edge of the flap may mate therewith.

2. An envelop including a rectangular front piece, an irregular back piece of less 25 length than the front piece, terminal extensions formed on the front piece, said extensions being disposed to mate with the back piece to form in connection therewith the back wall of the envelop, the adjacent edges 30 of the back piece and extensions being disposed to abut, sealing strips disposed within the envelop to connect the back piece and extensions, and a closure flap formed on the front piece.

In testimony whereof I hereunto affix my signature in the presence of two witnesses.

LOYAL M. DODDRIDGE.

Witnesses:

WILLIAM S. FRENCH,
CLYDE H. SMITH.
